FIG. 1.

FIG. 2.

FIG. 3.

By

AM Wilson

Attorney

UNITED STATES PATENT OFFICE.

PAUL NIZNIK, OF BINGHAMTON, NEW YORK.

PORTABLE BARRIER.

1,276,100.

Specification of Letters Patent. Patented Aug. 20, 1918.

Application filed December 22, 1917. Serial No. 208,439.

To all whom it may concern:

Be it known that I, PAUL NIZNIK, a citizen of the United States of America, residing at Binghamton, in the county of Broome 5 and State of New York, have invented certain new and useful Improvements in Portable Barriers, of which the following is a specification.

The primary object of the invention is the 10 provision of a device especially adapted for use in time of war for impeding the progress of the enemy and readily carried by soldiers for positioning upon the ground in its operative arrangement.

15 A further object of the device is the provision of a foldable member light in weight although possessing great strength adapted for arrangement upon the ground by retreating soldiers within the path of travel 20 of the pursuing army, whereby the enemy will be injured and hindered in its movement.

With these general objects in view and others that will appear as the nature of the 25 invention is better understood, the same consists in the novel combination, construction and arrangement of parts hereinafter more fully described, illustrated in the accompanying drawing, and then claimed.

30 In the drawing forming a part of this application and in which like designating characters refer to corresponding parts throughout the several views,

Figure 1 is an elevational view of the device.

35 Fig. 2 is a sectional view thereof taken upon line II—II of Fig. 1, and

Fig. 3 is an end view of the device.

The invention broadly consists of a fold- 40 able frame or grating 10 formed of pivot- ally connected strips 11 in lazy-tongs ar- rangement provided with a binding member or cross-piece 12 at one end thereof.

The frame may be readily folded against 45 the cross-piece 12 and secured in its closed arrangement by means of a strap 13 centrally secured to the said cross-piece while a neck strap 14 is carried by the cross-piece and by means of which the device may be 50 easily carried by a soldier by positioning the

said strap 14 either upon his arm or around his neck. Side plates 15 are carried by the cross-piece having slots 16 therein for slidably receiving the pivots 17 of the adjacent strips 11, whereby the amount of relative 55 movement between the said strips is limited. The pivots 18 for the strips 11 are in the form of spikes having pointed ends 19 projecting from the frame 10 at one side of the device. 60

A central plate 20 is provided for the cross-piece 12 intermediate the end plates 15 with the short adjacent end strips 21 of the lazy-tongs frame pivoted thereto. It will be understood that at the opposite end of 65 the frame 10 from the cross-piece 12, two short strips 21' corresponding to the strips 21 will be arranged pivotally connected together at their inner ends by a pointed bolt 22. The full length strips 11 are each ar- 70 ranged with a pivot spike 18 at each end and also at three intermediate points so that the completed device presents five complete rows of pivoting spikes, excepting spikes which will be arranged at the free ends of 75 the terminal strips 11 and these will have no pivotal operation.

The soldier may readily carry this invention and when forced to retreat, the strap 13 may be released for opening the frame 10, 80 slightly separating the strips 11 and a large number of the devices being thrown upon the ground with the spikes 18 extending upwardly, the progress of the enemy will be greatly impeded by stepping upon the said 85 spikes. A serviceable and light barrier is provided which may be readily used by soldiers to prevent capture.

What I claim as new is:—

1. A portable barrier comprising a lazy- 90 tongs frame having pivot bolts sharpened and projecting from one side thereof, a cross-piece at one end of the frame, limit- ing means for the lazy-tongs carried by said cross-piece, a retaining strap for the 95 lazy-tongs when closed centrally carried by the cross-piece and a carrying strap attached to the latter.

2. A portable barrier for army use com- 100 prising a cross-piece, plates carried by the

ends of the cross-piece arranged with vertical slots therein, a frame of lazy-tongs construction slidably attached within the slots of said plates for limited opening movement, 5 the said frame having pivot members, pointed extensions carried by said pivot members at one side of the frame project-

ing upwardly when the device is operatively positioned upon the ground, and retaining and carrying straps provided upon said 10 crosspiece.

In testimony whereof I affix my signature.

PAUL NIZNIK.
